(57) **CLAIM**

The ornamental design for a food product, as shown and described.

DESCRIPTION

FIG. 1 is a front right perspective view of a food product showing my new design;

FIG. 2 is a front elevation view of the food product shown in FIG. 1;

FIG. 3 is a rear elevation view of the food product shown in FIG. 1;

FIG. 4 is a right side elevation view of the food product shown in FIG. 1;

FIG. 5 is a left side elevation view of the food product shown in FIG. 1;

FIG. 6 is a top plan view of the food product shown in FIG. 1; and,

FIG. 7 is a bottom plan view of the food product shown in FIG. 1.

The broken lines shown in FIGS. 1–7 illustrate portions of the food product that form no part of the claimed design.
